ELECTRIC SWITCH

Wilbur F. Hurlburt, East Orange, and Frederick M. Vogel, Glen Ridge, N. J., assignors to Automatic Switch Co., New York, N. Y.

Application January 5, 1931. Serial No. 506,534

9 Claims. (Cl. 200—111)

Our present invention relates generally to electric switches, and has particular reference to a type of switch which is primarily adapted for remote control operation.

5 A general object of our invention is to provide a switch which may be applied or mounted on a panel board or the like in an extremely simple and efficient manner for the purpose of controlling the establishment and breaking of certain electrical connections between bus bars or the like mounted on the panel board.

Another general object of our invention is to provide an improved and simplified switch of the type wherein the complete operation of the 15 switch, for circuit opening or circuit closing purposes, is effected primarily by the momentum or inertia of a movable control member whose movements are initiated by an externally applied force, such as that afforded by an electromagnet 20 or solenoid.

Although we have herein illustrated and shall hereinafter describe a two-hole, single-throw switch, it will be understood that certain phases 25 of our invention are not restricted to a particular application of this character and that the essential features of our invention are capable of embodiment in a variety of other types of switches.

Before describing the features of our invention in greater detail, we will premise that where 30 two spaced and aligned bus bars have heretofore been arranged upon a panel board, the installation of a switch between these bus bars for the purpose of making and breaking an electrical connection between them has entailed the painstaking and accurate extra labor of drilling holes in the panel board, or taking similar steps, for 35 the purpose of accommodating a switch in a properly accurate positional relationship to the bus bars. Such switch customarily is provided with a brush or its equivalent whose opposite ends arrange themselves over the spaced bus bars, respectively. When the contact is to be 40 closed, the brush moves downwardly onto the bus bars; and when the contact is to be opened, the brush rises from the bus bar. If the switch is 45 not accurately positioned on the panel board, the brush will not make accurate and efficient contact at its opposite ends with the bus bars 50 involved.

It is one object of our present invention to provide a switch whose installation under conditions of the foregoing illustrative character has been greatly simplified, and whose subsequent 55 operation is always accurate and of maximum ef-

iciency so far as closure of electrical connections between the bus bars is concerned.

In accordance with this general object, it is a feature of our invention to provide a switch wherein a housing is provided with attachment 60 lugs or extensions each of which is, in effect, a bus bar section coacting with a brush or its equivalent accurately and properly arranged within the housing during the manufacture of the switch. In mounting the switch upon the 65 panel board, the attachment extensions engage with the bus bars involved and serve at one and the same time to secure the switch to the panel board and also virtually to extend the bus bars into the housing of the switch itself. 70

Another general object of our invention is to provide a switch which may be installed and operated with equal facility and efficiency in either a vertical or a horizontal position, or, for that matter, in any desired position or inclination. 75

In accordance with the last-mentioned object, it is a feature of our invention to provide a construction wherein the movable control member, whose inertia or momentum is material in effecting the operation of the switch, is so constructed 80 and arranged that the movements thereof are unaffected by the disposition or angular inclination of the switch itself.

Thus, it is a feature of our invention to provide a switch of the foregoing character, wherein the weight of the movable control member is eliminated as a factor which affects the switch operation, except in so far as such weight increases the inertia and mass of the movable control member. More particularly, we provide an arrangement 85 whereby the force of gravity upon the center of gravity of the movable control member is powerless to affect the contemplated movements and operative effects of the control member. 90

In the construction herein illustrated by way of example, the movable control member is in the form of a drum rotatably mounted upon an axis coincident with the center of gravity of the drum. The drum is adapted to be oscillated or reciprocated in an angular manner about this axis, and, obviously, the force of gravity operates upon the rotational axis but does not affect the movements of the drum around this axis. 100

The external means which we prefer to employ for the purpose of initiating the movements of the control member or drum is a solenoid, the movable core of which is articulated in a particular manner with the control drum. To energize and deenergize the magnetic coil, an electric con- 105

trol circuit is provided for permitting operation of the switch from a remote point. In accordance with the contemplated operation of our switch, the magnetic coil is automatically de-energized after the movement of the control member or drum has been initiated. This automatic deenergization is effected by a make-and-break arrangement controllable by the movements of the drum itself, and, in accordance with 10 our present invention, this arrangement is constructed in a novel and highly efficient manner.

Our invention also provides improved means for automatically locking the switch in each of its positions, this locking means being independent 15 of the action of the weight of the control member.

Other features of our invention lie in the particular construction and arrangement of parts which renders our present switch relatively simple 20 in structural nature, inexpensive to manufacture, easy to install, reliable and efficient in operation, and also rugged and staunch and unsusceptible to the influence of vibrations and the like.

We achieve the foregoing objects, and such other objects as may hereinafter appear or be pointed out, in the manner illustratively exemplified in the accompanying drawings, wherein—

Figure 1 is a plan view of a switch of the present character applied to a panel board, the top of the switch being broken away for the sake of clearness;

Figure 2 is an elevational cross-sectional view taken substantially along the line 2—2 of Figure 1, and showing also at the line 1—1 the direction in which Figure 1 has been taken;

Figure 3 is a transverse cross-sectional view taken substantially along the line 3—3 of Figure 2;

Figure 4 is an elevational cross-sectional view taken substantially along the line 4—4 of Figure 1;

Figures 5 and 6 are views similar to Figure 2, showing the relationship of the parts during operation of the switch;

Figure 7 is a cross-sectional view taken substantially along the line 7—7 of Figure 2, and illustrating the electric control circuit;

Figure 8 is an elevational cross-section taken substantially along the line 8—8 of Figure 1; and

Figure 9 is a cross-sectional view taken substantially along the line 9—9 of Figure 1.

In the construction herein illustrated, we have shown a switch of the present character mounted upon a panel board 10 in association with two pairs of aligned and spaced bus bars. More particularly, we have shown a bus bar 11 spaced from and aligned with a bus bar 12, and we have shown a bus bar 13 spaced from and aligned with a bus bar 14. The panel may be of any suitable material, such as slate or ebony asbestos, and the bus bars are secured to the surface thereof in any desired manner, preferably by means of studs whose upper or outer threaded ends extend through the ends of the bus bars, respectively, for a purpose presently to be described. In Figure 4, for example, a stud 15 of this character has been illustrated in association with the bus bar 11, and a similar stud 16 extends upwardly through the end of the bus bar 12. Similar studs 17 and 18 are associated with the bus bars 13 and 14, respectively.

In accordance with our present invention, the switch is mounted on the panel 10 in the space between the bus bars, and the function of the switch in connection with these bus bars will be

to make and break electrical connections, at predetermined times, between the bus bar pair 11 and 12 and between the bus bar pair 13 and 14. The switch illustrated is thus a two-pole, single-throw switch.

The housing of the switch which we have shown is composed of two main parts, a base, which is preferably made entirely of insulating material, and a cover, which may be of any suitable material, such as cast iron or pressed steel. The housing, and, more especially, the base thereof, is provided with a series of attachment elements or lugs which project laterally and are adapted to accommodate studs or similar instrumentalities for mounting the entire housing in a predetermined position upon its contemplated support. In accordance with our present invention, these attachment elements are of conductive material and are arranged to project at opposite sides of the housing in such a manner that they may be, respectively, brought into direct engagement with the bus bars 11—14. In Figures 1 and 2, for example, it will be noted that an attachment element 19 is adapted to engage over the stud 15, a nut or the like 23 engaging with this stud to secure the element 19 to the panel and to hold this element and the bus bar 11 in firm contacting engagement. Similarly, attachment elements 20, 21, and 22 are secured to, and contact with, the bus bars 12, 13, and 14, respectively.

In the illustrated form, the elements 19—22 are themselves composed of bus bar material, such as copper, and each one is in the form of a strip which is arranged in countersunk relationship within the bottom surface of the base of the housing. Referring to Figure 7, for example, the conductive strip 19 is secured to the base 24 by means of a stud 25 which extends upwardly into the base. Similarly, the strips 20, 21, and 22 are secured to the base by means of studs 26, 27, and 28, respectively. In Figure 7, the openings in the projecting portions of the elements 19—22 are clearly discernible, these openings being adapted to engage over the studs 15—18 which are associated with the ends of the bus bars 10—14.

The base of the housing is illustrated most clearly in Figure 7, is substantially rectangular, and has a substantially flat bottom 29 provided with upstanding corner portions or pedestals 30, 31, 32, and 33. Projecting upwardly through these pedestals are a series of studs 34, the heads of which are countersunk in the bottom surface of the base 24, and the threaded ends of which project upwardly to receive and support attachment lugs 35 provided on the cover. Nuts 36 engage with the studs 34 to hold the housing in assembled condition.

In the floor 29 of the base of the housing are four openings 37, 38, 39, and 40, within which the inner ends of the attachment elements 19—22, are, respectively, disposed as shown most clearly in Figure 7. It is through the openings 37 and 38 that a brush, presently to be described, gains access to the elements 19 and 20 for the purpose of establishing and breaking an electrical connection between them; and it is through the openings 39 and 40 that a similar second brush, presently to be described, fulfills the same general function in connection with the conductive strips 21 and 22.

Projecting upwardly from the floor 29 of the base are a series of partitions of arc barriers which help to shield the inner ends of the ele-

ments 19-22. Thus, an upstanding wall 41 is arranged alongside of the element 19, and similar walls 42, 43, and 44 are arranged in corresponding positions with respect to the other attachment elements.

A pair of substantially circular openings 45 and 46 are also provided in the base 29 substantially midway thereof for a purpose presently to be described.

10 The top portion or cover of the housing is provided with a top wall 47 and depending side walls 48 and 49, and an end wall 50. The opposite end wall 51 is preferably provided with a large aperture through which a portion of the drum of the 15 device is adapted to project, although this structural arrangement is not essential.

Extending downwardly from the top wall 47, at approximately the midportion of the housing, is a wall 52, the center portion of which extends 20 downwardly into the housing for a substantial distance, as shown at 53 in Figure 3, for the purpose of providing a bearing for the solenoid core presently to be described, and also to complete the magnetic circuit of the solenoid. The portions 25 of the wall 52 lying adjacent to the side walls 48 and 49 are slightly thickened, as at 54 and 55 (Figure 3), and are provided with substantially parallel bores adapted to serve as bearings, respectively, for a pair of brush-supporting rods 56 and 57. As viewed in Figure 3, the axis 30 of the bearing in the portion 53 is substantially horizontal, while the axes of the bearings in the portions 54 and 55 are substantially vertical, but, as will be pointed out hereinafter, the entire 35 switch need not necessarily be arranged in this position, nor in any other particular position relative to the horizontal.

Referring for the moment to Figure 3, it will be noted that the midportion of the rod 56 is 40 provided with a laterally projecting pivot pin 58. This pin is articulated to the midportion of a lever 59 presently to be described in greater detail. One end of this lever is pivoted to a fixed pin 60 mounted in the side wall 48. At its lower 45 end, the rod 56 is secured to a cross beam 61 which is of insulating material and which carries the brushes. In the form shown, the lower end of the rod 56 is threaded, passing completely through the beam 61, and a nut 62 engages its 50 lower end.

The rod 57 is similarly provided with a pin 63, a lower threaded end, and a nut 64. The pin 63 engages with a lever 65 fixedly pivoted at one end, as at 66, to the wall 49.

55 The midportion of the beam 61 is concaved on its upper surface so that the reciprocation of this beam may be effected with due regard for the bearing portion 53 of the wall 52.

The axes of the rods 56 and 57 are aligned 60 with the axes of the holes 46 and 45, respectively, and the reason for these holes will now be obvious, viz, to provide accommodation for the nuts 62 and 64 when the beam 61 is reciprocated.

At one end, the beam 61 carries a brush, designated generally by the reference numeral 67, which cooperates with the conductive elements 21 and 22; and at the opposite end, the beam 61 carries a similar brush, designated generally by the reference numeral 68, which coacts with the 70 elements 19 and 20. The latter brush is most fully illustrated in Figure 4, and a description thereof will serve as a description of both brushes, since they are alike.

The end of the beam 61 serves as a sort of 75 saddle upon which a series of superposed copper

strips 69 are mounted. Over the outermost of these strips is a spacing strip 70, preferably of phosphor bronze, and on top of this is a second phosphor bronze strip 71 riveted at its free end to a pair of relatively heavy and doubled-back 80 copper or silver-tipped elements or arc fingers 72. A brass element 73 is laid over the strip 71, and a stud 74 unites the entire construction into a single device firmly mounted upon the end of the beam 61.

The brush is, obviously, of a flexible character, and although it is shown in a retracted inoperative position in Figure 4, it will be obvious that when the beam 61 is moved toward the base 29, the opposite ends of the brush will frictionally 90 engage in a proper manner with the elements 19 and 20, respectively, thereby establishing an electrical connection between them.

The brushes 67 and 68 are thus mounted for reciprocal movement toward and away from their 95 corresponding pairs of conductive strips. This movement is guided by the rods 56 and 57, and is effected by movements of the levers 59 and 65, the operation of which will now be described in greater detail.

A drum 75 of substantially cylindrical configuration and of relatively weighty material is mounted for rotational oscillation between the opposite side walls 48 and 49. More particularly, it is mounted closely adjacent to the end wall 51 105 on a shaft or spindle 76 which is journaled in the opposite side walls. On its end surfaces, the drum is provided with a pair of concentrically arranged crank pins 77 and 78, respectively. The pin 77 is engaged by the forward slotted or forked end 79 of the lever 65, and the pin 68 is engaged 110 in a similar manner by the forked end 80 of the lever 59.

The drum 75 is adapted to be reciprocated around its axis from the extreme position of 115 Figure 2 to the opposite extreme position of Figure 6. In moving from one of these positions to the other, the pins 77 and 78 effect a pivotal movement of the levers 59 and 65, as a result of which the pins 58 and 63 are simultaneously 120 impelled downwardly or upwardly, as the case may be, thereby effecting the desired movement of the beam 61 and of the brushes carried by the latter.

In accordance with our invention, the movements of the drum 75 out of its extreme positions are initiated by external means, preferably electromagnetic, as, for example, a solenoid. The completion of each movement of the drum 75 from one of its extreme positions to the other is 130 effected independently of the external means and solely by virtue of the momentum or inertia of the drum itself.

With this general objective in view, we provide 135 a magnetic coil 81 within the housing, this coil being substantially cylindrical, with a bore through its axis. The magnet may, for example, be mounted upon a tubular support 82 which is mounted at its forward end in the portion 53 of the wall 52. Within this tube, a solenoid core 83 140 is arranged for sliding axial reciprocation. Preferably, though not necessarily, the core is provided with a bore adapted to receive the forward end of a compression spring 84, the rear end of this spring being footed upon a pin 85 mounted 145 in the end wall 50, and, preferably, in screw-threaded engagement with the latter, as shown at 86.

At its forward end, the core 83 is slotted, and 150 one end of a connecting rod 87 is pivoted, as at 88,

within this slot. The other end of the connecting rod is pivoted, as at 89, within the slot or space formed between the two upstanding lips 90 formed on the midportion of the drum 77. The pin 89 is virtually a crank pin, and cooperates with the connecting rod 87 and the core 83 in the same manner as though the core 83 were a cross-head of an engine.

The core 83 is normally in the position shown in Figure 2, the magnet being deenergized and the spring 84 urging the core toward the right, as viewed in this figure. The core abuts against the drum 75 and is thereby held in the position shown under normal conditions. When the solenoid is energized, in a manner presently to be described, the core 83 is drawn into the magnetic coil against the action of the spring 84, and this movement is transmitted through the connecting rod 87 to the drum 75 and initiates a rotational movement of the drum.

In accordance with our invention, the magnet becomes automatically deenergized after a predetermined initial movement of the drum 75, whereby the momentum of the latter is permitted to complete its oscillation into the position of Figure 6, this complete movement, enhanced by the action of the spring 84, serving to return the core 83 to its normal projecting position. The connecting rod 87, however, will have been moved from the inclined position of Figure 2 to the oppositely inclined position of Figure 6.

The energization and deenergization of the electromagnet is effected by means of an auxiliary electric circuit and an automatic circuit-breaking switch in this circuit and controllable by the drum 75 itself. Before describing this circuit, we will point out that a lever 91, of insulating material, is loosely mounted at one end to the shaft 76, and is provided at its opposite end with a transversely arranged rod 92 of conductive material, preferably brass, the opposite free ends of this rod being provided with contact collars, preferably of a silver alloy or the like. The lever 91 is mounted on the shaft 76 substantially midway of the latter, and this is made possible by providing a transverse slot or channel within the drum 75 in the manner clearly indicated in the drawings, and, more especially, in Figures 2, 5, and 6.

Mounted within the last-mentioned channel or recess is a U-shaped spring 93, secured as at 94 to the drum 75, and provided with the two opposed spring fingers 95 and 96. This spring is so mounted and arranged that when the drum is in the position of Figure 2, the finger 96 will bear against the lever 91 and urge the latter in a clockwise direction in a yieldable manner. At this time, the spring finger 95 is inoperative, but as soon as the drum 75 approaches its opposite position, as shown in Figure 6, the finger 95 becomes operative to bear against the opposite side of the lever 91 and urge the latter in a counterclockwise direction, as shown most clearly in Figure 6.

Mounted on the base 29 are four upstanding spring contacts 97, 98, 99, and 100, these being preferably made of brass or silver-copper alloy and being secured to the base in any desired manner. The contacts 97 and 99 are arranged side by side and are adapted to be encountered by the opposite ends of the rod 92 when the drum 75 is in the position of Figure 2. The contacts 98 and 100 are positioned in an opposed manner, also side by side, and are adapted to be encountered by the rod 92 when the drum is in its opposite extreme position, as shown in Figure 6. Thus, in Figure 2, the spring finger 96, through its action

on the lever 91, is holding the rod 92 firmly against the contacts 97 and 99, this rod thereby establishing a series connection between these contacts. Similarly, in Figure 6, the spring finger 95, through its action on the lever 91, is holding the rod 92 firmly in contact with the spring contacts 98 and 100, thereby establishing a direct series connection between them.

The electrical circuit for controlling the solenoid is shown most clearly in Figure 7. Three binding posts 101, 102, and 103 are preferably employed, and are mounted on the side of the base of the housing in the adjacent spaced relationship shown in Figure 1. From the terminal 101 a suitable lead 104 connects with one end of the magnet 81. The other end of the magnet is connected by a lead 105 to the contact 97. The contact 97 is integral with the contact 98, and is preferably constructed in the U-shaped manner shown in Figure 2 from a single strip of material.

From the terminal 102 a lead 106 connects with the contact 99, and a similar lead 107 connects the binding post 103 with the contact 100.

Leads extend from the binding posts 101, 102, and 103 to any convenient point of control, usually at a distance from the switch. A momentary contact button, for example, which might be termed the "on" button connects in this way with the binding posts 101 and 102. A similar button, which may be termed the "off" button, connects with the terminals 101 and 103.

As a result of the foregoing arrangement, the operation of the switch is as follows: Assuming the parts to be in the normal inoperative relationship of Figure 2, an actuation of the "on" button at a remote point will cause a control current, usually the ordinary 110-volt supply, to pass through the contact 99, the rod 92, and the contact 97 for the purpose of energizing the solenoid 81. This causes the core 83 to be attracted into the solenoid and initiates a rotational movement of the drum 75 out of the position of Figure 2 and in a counterclockwise direction. During about 30° of this movement, the spring finger 96 remains operative upon the lever 91 so as to maintain the auxiliary circuit. The movement of the drum having thus been initiated, the finger 96 will presently release its pressure upon the lever 91, so that the parts will presently assume the position of Figure 5. Thereafter, the spring finger 95 becomes operative to push the lever 91 into the position of Figure 6, thereby breaking the series connection between the contacts 97 and 99. This will break the auxiliary circuit and deenergize the magnet, as a result of which the complete throw of the drum 75 will be caused to continue solely by virtue of the momentum thus far imparted to it by the outside means. The solenoid being deenergized, the core 83 is free to return to its normal position under the action of the spring 84 and also by virtue of the pull thereon by the connecting rod 87.

This throw of the drum 75 from one extreme position to the other is thus effected in a fraction of a second, and causes the brushes 67 and 68 to move suddenly downwardly into their operative positions, at which time the brush 67 will contact simultaneously at both of its ends with the conductive strips 21 and 22, while the brush 68 will establish a similar electrical connection between the strips 19 and 20.

The brushes will be locked in this position by virtue of the fact that upward movement thereof would necessitate an upward swing of the levers 59 and 65, which is obviously impossible,

upon viewing Figure 6, unless the drum itself is caused to rotate in the return direction.

While the switch is thus operative, it is obvious that the auxiliary circuit broken at 97 and 5 99 will have been reestablished at 98 and 100. As a result, any subsequent operation of the "off" button will serve in the same manner momentarily to energize the solenoid for the purpose of initiating the return movement of the drum from 10 the position of Figure 6 to that of Figure 2. During this return movement, the rod 92 will remain in contact with the points 98 and 100, while the drum swings through approximately 30°, this being assured by the continuing action of the 15 spring finger 95 during this 30° movement. Thereafter, the momentum of the drum continues its movement and the solenoid is automatically deenergized.

When the brushes are in the inoperative positions, they are similarly locked against movement out of these positions by means of the levers 59 and 65, and the associated mechanisms.

The advantages of our present switch will be obvious from the description given. The axis of 20 rotational movement of the drum 75 passing practically through the center of gravity of the drum, the weight of the latter does not affect or interfere with the proper operation of the switch except in so far as this weight contributes 25 to the inertia and mass of the drum. Whether the switch is arranged upon a horizontal panel or upon a vertical panel, or whether it be mounted in any other inclination or arrangement, the contemplated operation will always take place in 30 the manner described.

Since the arrangement of the strips 19-22 is provided for during manufacture, the initial mounting and assembly of the parts to assure proper contact between each brush and its two corresponding conductive strips will always be accurately the same and will not depend upon the haphazard judgment or skill of any outside workmen who may be called upon to install the switch. The strips 19-22 virtually carry the 45 outside bus bars into the interior of the switch, so that the proper functioning of the brushes may be controlled by the manufacturer of the switch, and will be independent of any particular pains or care that may be necessary in installing 50 the switch upon a panel.

A further advantage is obviously the one which dispenses with the necessity for accurate or predetermined drilling of additional holes in the panel for the purpose of mounting the switch. 55 If the outside bus bars are properly spaced to start with, usually in accordance with specifications supplied by the switch manufacturer, it is necessary for the installer merely to apply the switch to the studs 15-18 and then tighten up 60 upon the nuts engaging these studs. Not only is extra labor and time avoided in this manner, but the necessity for extra parts and attachment lugs and the like is rendered entirely unnecessary. Of most importance is the ease and 65 simplicity with which the switch may be expeditiously applied to its contemplated position with the unfailing assurance that its operation thereafter will be accurate and uniformly efficient. Replacement is also simplified and expedited.

70 By the same token, it is obvious that vibrations and jarring will not affect the switch, nor its proper functioning.

A further advantage of our present construction lies in the fact that no auxiliary current 75 need be maintained. The solenoid is normally

deenergized and current is caused to pass through it only for a fraction of a second whenever the switch is desired to operate. As a result, extra parts, resistances, and similar devices and expedients are completely avoided.

80

Another advantage lies in the fact that the present switch is "dead", as will be obvious from the description given. No contact with the switch, other than deliberate contact with the operative brushes, can possibly cause current to pass through the person making the contact. If desired, even the brushes may be completely enclosed and guarded.

85

Obviously, our invention is not restricted to the particular construction illustrated. A three-pole switch might, for example, be constructed in accordance with the same principles, it being merely necessary to mount an additional brush upon the beam 61 and to arrange an additional pair of conductive attachment elements in operative relationship to the brush. Similarly, any multipole switch may be constructed by simply duplicating these parts.

90

Where desired, a manually controllable handle, such as that shown at 108, may be mounted 100 upon the end of the shaft 76 so as to permit operation of the switch to be effected independently of the auxiliary control circuit.

95

Other changes and modifications will readily suggest themselves to those who are conversant 105 with this general art, and, in general, it will be obvious that changes in the details herein described and illustrated for the purpose of explaining the nature of our invention may be made by those skilled in the art without departing from 110 the spirit and scope of the invention as expressed in the appended claims. It is therefore intended that these details be interpreted as illustrative, and not in a limiting sense.

100

Having thus described our invention, and illustrated its use, what we claim as new and desire to secure by Letters Patent is—

115

1. In an electric switch of the character described, a movable contact brush, a pivotally mounted, relatively weighty member for controlling the movements of said brush, the center of gravity of said member coinciding with its pivot axis, electromagnetic means for initiating the movement of said member, and means operable by said member after its movement has 120 been initiated for rendering said electromagnetic means inoperative.

120

2. In an electric switch of the character described, a movable contact brush, a weighty movable member for controlling the movements of said brush, and electromagnetic means for initiating the movement of said weighty member; said member being mounted for rotational movement about an axis passing through its center of gravity, whereby the functioning of the switch 130 remains unaffected in all positions thereof.

130

3. In an electric switch of the character described, a movable contact brush, a relatively weighty, substantially cylindrical drum mounted for rotational oscillation about its axis, said drum controlling the movements of said brush, and electromagnetic means for initiating the oscillations of said drum.

140

4. In an electric switch of the character described, a movable contact brush, a relatively weighty, substantially cylindrical drum mounted for rotational oscillation about its axis, said drum controlling the movements of said brush, and means eccentrically engaging said drum for locking said brush against further movement after 145 150

155 said brush against further movement after 150

its desired movement has been effected.

5. In an electric switch of the character described, a contact brush mounted for bodily reciprocation between two extreme positions, a relatively weighty, substantially cylindrical drum mounted for rotational oscillation about its axis and controlling the reciprocations of the brush, and means eccentrically engaging said drum for locking said brush against movements out of said extreme positions except during oscillations of the drum.

6. In an electric switch of the character described, a contact brush mounted for bodily reciprocation between two extreme positions, a relatively weighty, substantially cylindrical drum mounted for rotational oscillation about its axis and controlling the reciprocations of the brush, a crank pin carried eccentrically by said drum, and a slotted lever engaging said pin and articulated to said brush to lock the latter against retractive movements out of said extreme positions.

7. In an electric switch of the character described, a contact brush mounted for bodily reciprocation between two extreme positions, a relatively weighty, substantially cylindrical drum mounted for rotational oscillation about its axis and controlling the reciprocations of the brush, a crank pin carried eccentrically by said drum, and a slotted lever engaging said pin in said slot

and pivoted to a fixed point at its opposite end, said lever being pivoted between said end and said slot to said brush, so as to lock the latter against movement out of its extreme positions.

8. In an electric switch of the character described, a movable contact brush, a relatively weighty, substantially cylindrical drum mounted for rotational oscillation about its axis, said drum controlling the movements of said brush, and electromagnetic means for initiating the oscillations of said drum; said electromagnetic means comprising a solenoid with a reciprocable core, and a connecting rod pivoted at one end to said core and pivoted at its other end to an eccentric point on said drum.

9. In an electric switch of the character described, a movable contact brush, a relatively weighty, substantially cylindrical drum mounted for rotational oscillation about its axis, said drum controlling the movements of said brush, and electromagnetic means for initiating the oscillations of said drum; said electromagnetic means comprising a solenoid with a reciprocable core, a spring urging said core away from the position it is attracted into by said solenoid, a crank pin on said drum, and a connecting rod between said core and said crank pin.

WILBUR F. HURLBURT.
